[57] CLAIM

The ornamental design for a combined lamp, battery and mounting clip assembly for attachment on a fishing pole near the tip thereof, as shown and described.

DESCRIPTION

FIG. 1 is a top, front perspective view of a combined lamp, battery, and mounting clip assembly for attachment on a fishing pole tip showing my new design; FIG. 2 is a top plan view thereof on an enlarged scale; FIG. 3 is a side elevational view thereof on an enlarged scale, the opposite side being a mirror image; FIG. 4 is a front elevational view thereof on an enlarged scale;

FIG. 5 is a rear elevational view thereof on an enlarged scale; and

FIG. 6 is a bottom plan view thereof on an enlarged scale.
